UNITED STATES PATENT OFFICE.

WILLIAM B. WARREN, OF ST. LOUIS, MISSOURI.

LOCOMOTIVE-BOILER.

SPECIFICATION forming part of Letters Patent No. 716,600, dated December 23, 1902.

Application filed April 4, 1902. Serial No. 101,362. (No model.)

To all whom it may concern:

Be it known that I, WILLIAM B. WARREN, a citizen of the United States, residing in the city of St. Louis, in the State of Missouri, have 5 invented certain new and useful Improvements in Locomotive-Boilers, of which the following is a full, clear, and exact description, reference being had to the accompanying drawings, forming part of this specification.

10 My invention relates to a dry-pipe system, whereby dry steam is delivered from a locomotive-boiler to the locomotive-cylinders.

The invention consists in features of novelty hereinafter fully described, and pointed 15 out in the claims.

Figure I is a longitudinal section of a locomotive-boiler equipped with my invention. Fig. II is an enlarged detail vertical section taken on line II II, Fig. I. Fig. III is an enlarged horizontal section taken on line III III, Fig. I.

1 designates a locomotive-boiler containing the usual tubes 2.

3 and 4 designate a series of steam-domes 25 that surmount the boiler 1 and have communication therewith.

5 is a steam-receiving pipe open to communication with the upper part of the steam-dome 3 to receive dry steam, and 6 represents 30 steam-receiving pipes open to communication with the upper part of the steam-domes 4 to receive dry steam.

7 is a steam-box to which all of the pipes 5 and 6 lead to deliver dry steam thereinto from 35 the domes 3 and 4, and 8 is a neck extending into said box and provided with apertures 9 for the passage of steam therethrough from said box from above and below the neck.

10 designates a pipe-leg having its upper 40 end seated in the neck 8 of the steam-box 7 and provided with upper and lower ports that register with the respective apertures 9 in the neck 8.

11 is a steam-conducting pipe that leads 45 from the pipe-leg 10 to the exterior of the boiler 1 and through which the steam passes to be delivered to the locomotive-cylinders.

12 is a double throttle-valve positioned in the upper end of the pipe-leg 10 within the 50 steam-box 7 and adapted to control both the upper and lower ports therein. This throttle-valve is operated by any suitable means,

such as the bell-crank 13, that is connected to the stem of said valve and receives the connection of an operating-rod 14. 55

It will be seen from the foregoing that the dry steam that rises into the domes 3 and 4 is constantly delivered from all the domes into the single steam-box 7 for delivery therefrom and that upon the actuation of the throttle-valve 12 to open the ports in the neck of the pipe-leg 10 the accumulated steam escapes freely from said box into said pipe-leg, from which it passes directly into and through the conducting-pipe 11. 60 65

The advantages incident to my invention are as follows: A more equal withdrawal of steam from different points of the boiler is derived than in the dry-steam systems heretofore in use, and therefore less suction is present at any point of the boiler and less priming and foaming are necessary and occasioned, thereby providing for the delivery of drier steam from the boiler. By reason of the advantageous features mentioned it is possible 70 to obtain greater service from the locomotive-boiler and accomplish greater mileage of travel in its use between periodical cleansing of the boiler, thus providing material saving of time and causing less trouble and annoyance from leaky boilers and breakage of stay-bolts incident to frequent washing out of the locomotive-boiler. 75 80 85

I claim as my invention—

1. The combination with a locomotive-boiler, of a series of steam-domes surmounting the boiler, a steam-box located entirely within one of said domes and having communication with each of said domes, a steam-conducting pipe leading from said steam-box 90 and having communication therewith, and a throttle-valve arranged to control the passage of steam from said box to said conducting-pipe, substantially as described. 95

2. The combination with a locomotive-boiler, of a series of steam-domes surmounting the boiler, a steam-box located entirely within one of said domes, steam-receiving pipes open to communication with the interior of each of said domes and leading to said steam-box, a steam-conducting pipe leading from said steam-box and having communication therewith, and a throttle-valve arranged to control the passage of steam from said box 100

to said conducting-pipe, substantially as described.

3. The combination with a locomotive-boiler, of a series of steam-domes surmounting said boiler, a steam-box located in one of said domes, steam-receiving pipes leading from said domes into said box, a neck extending into said steam-box and having upper and lower apertures in communication with said box, a pipe-leg seated in said neck

and having ports providing communication from said box into said leg through the upper and lower apertures, a throttle-valve arranged to control said ports, and a steam-conducting pipe connected to said pipe-leg, substantially as described.

WILLIAM B. WARREN.

In presence of—
E. S. KNIGHT,
M. P. SMITH.
